UNITED STATES PATENT OFFICE

WILLIAM HATTON, ERNEST J. ROUSSEAU, AND GUSTAVE T. WARMOES, OF PARIS, FRANCE, ASSIGNEES TO WESTERN ELECTRIC COMPANY, INCORPORATED, OF NEW YORK, N. Y., A CORPORATION OF NEW YORK

TELEPHONE SYSTEM

Application filed October 23, 1931, Serial No. 570,522, and in France December 19, 1930.

This invention relates to telephone systems and more particularly to a circuit arrangement for dealing with faults or alarms which may occur in such systems.

5 An object of the invention is to provide an improved arrangement for transmitting alarm signals and is to provide better facilities for indicating at one point in a telephone network the presence of a fault at a 10 distant point in such a network.

According to one feature of the invention a circuit arrangement is provided in which the presence of a fault is adapted to be signaled over an outgoing junction by means 15 of impulses, a different number of impulses being transmitted according to the particular type of fault which is present.

A circuit arrangement may also be provided for indicating at an attended exchange 20 a fault which is present at an unattended exchange, the receiving mechanism at the incoming exchange being so designed as to discriminate between different types of faults or between a fault and an ordinary 25 call. The receiving mechanism may be arranged to indicate a fault or to transmit a corresponding signal to a further exchange in the network.

The circuit arrangement may be so 30 designed as to indicate at an attended exchange the presence of a fault at an unattended exchange, the recording mechanism at the attended exchange being so arranged as to indicate the particular exchange in 35 which such fault has occurred, provision also being made for indicating the type of fault which is present.

According to the preferred form of the 40 invention, each exchange in which a fault may occur is connected to a "center" exchange by a separate junction, and a single junction, over which alarm signals for all the exchanges are transmitted, connects the 45 "center" exchange to a main exchange. The identity of an exchange in which a fault occurs is recorded at the "center" exchange by a selector switch and a similar switch is provided at the "main" exchange which moves 50 in synchronism with the switch at the "cen-

ter" exchange to indicate the exchange having a fault at the "main" exchange.

The invention will be more completely understood from the following detailed description which is given in conjunction with 55 the accompanying drawings in which:

Fig. 1 shows a fault alarm circuit for indicating different types or classes of alarms by means of impulses.

Figs. 2 and 3 show a circuit arrangement 60 for use at a "center" and a "main" exchange respectively; which provide for receiving and extending the alarm signals transmitted from Fig. 1 and also for indicating at the "main" exchange the particular exchange or 65 district in which the fault has occurred.

Referring first to Fig. 1, the operation of the circuit for giving an alarm, and indicating the class of fault will first be described.

Any kind of alarm may be provided for, 70 and these may be divided into the urgent and the non-urgent variety as desired. The most common types of alarms are circuit fuse alarm, voltage alarm, motor failure alarm, main fuse alarm, and ringing alarm and of 75 these the first two are generally classed as being non-urgent and the last three as being urgent.

The apparatus for giving non-urgent alarms comprises relay Pr and contacts CFA 80 and VA controlled by the circuit fuse alarm and the voltage alarm respectively.

The apparatus for giving urgent alarms is connected to the winding of relay Ir .

If the motor should be out of order, thermostatic relay Sh operates after a time interval, via lead MS thereby operating Sk which locks and connects ground to the winding of Ir . A similar operation takes place when a shaft failure alarm occurs. Relays Mf and Ra operate in case of main fuse and ringing failure respectively and in either case Ir operates.

In all cases of alarms a circuit will be completed for relay A either over $pr1$ or $ir2$. 95 The windings of relay B , which controls the circuit for relay H , are connected via $a2$, $a3$ the incoming the outgoing junction circuits respectively of the both way junction so that if the junction is busy in either di- 100

rection B will operate when A pulls up and prevent relay H energizing.

When the junction is free H will energize via a_1 , b_1 , A junction to "center" is now 5 connected to the alarm circuit.

Relay H opens the outgoing junction; test battery is now connected to the "a" wire of the junction via h_2 and ground is connected to the "b" wire via h_5 , a_1 and a_1 , and b_3 , 10 to operate the bridged line relay J_b in the fault circuit at the incoming end of the junction.

When the junction is taken into use for a 15 normal call, the junction is looped and the fault line relay will not operate.

Relay A_c is operated over a_1 , a_2 , and h_5 . A circuit is now closed for relay A_i over a_2 and h_5 .

Relay A_i energizes slowly and when operated, 20 opens the ground on the "b" wire at contact 1, thereby sending an impulse to the next exchange. Relay A_i at its contact 3 also opens the circuit for relay A_c which de-energizes slowly and after release connects 25 again ground to the "b" wire.

If the alarm is non-urgent then relay I_r will not have been operated and relay A_i is therefore locked via i_1 , a_1 , a_2 , h_5 . A thermostat T_h is operated via a_2 , h_5 after 30 a time interval and energizes relay A_l , thereby releasing A_i and opening the initial energizing circuit of A_c . Relay A_l locks up until the fault is cleared preventing any further impulsing and disconnecting the thermostat.

If the alarm is urgent, relay I_r will be 35 operated and relay A_i will release when its operating circuit is opened at a_2 .

With A_i back, relay A_c will reoperate and the same cycle is repeated giving one impulse 40 at each operation of A_i .

The cycle is repeated until relay A_l is operated by the thermostat and locks disconnecting A_l and A_c at a_2 .

When the fault is cleared, the alarm 45 apparatus returns to normal, releasing relays A and H and A_l .

Referring now to Figs. 2 and 3, a circuit is shown for signaling urgent and non-urgent alarms from the circuit shown in Fig. 1 via 50 a "center" exchange (Fig. 2) to a "main" exchange (Fig. 3) and for indicating in the "main" exchange the particular outgoing exchange in which the fault is present.

It is to be understood that in Fig. 2 the 55 switch C_{sm} together with relays S_t , S_{r_1} , S_{r_2} , T , F , F_o and B is common to all junctions incoming from the district exchanges, while relays S, O, C, J_b , J_r , E and A_c are individual to each incoming junction. One incoming junction is represented by the leads a , b .

When a fault occurs in a district exchange, 60 an alarm impulse will be sent out from a circuit associated with the district exchange, such as that shown in Fig. 1 over the "a" and "b" wires thereby operating relay J_b 65

which operates J_r over jb_1 . When the alarm impulse is completed relay J_b falls back and removes the short circuit from the left hand winding of relay A_c which thereupon operates from battery two windings of A_c , e_2 , jr_1 . The operation of A_c closes the circuit of B; battery, windings of B, ac_3 , ac_4 , ground. Relay B operates if the junction is free, the relay being short circuited to ground on cb_1 if the junction is busy, since under the latter condition Cb will be operated. 70 75

When B operates, it closes a circuit for S_t over b_1 and f_0 , connects the "a" wire of Fig. 3 to ground over b_4 , and ac_4 and connects the "b" wire over b_3 , ac_2 , f_0 , t_4 , interrupter 80 of the selector C_{sm} to battery.

Relay S_t in operating, closes a circuit for the magnet C_{sm} ; ground INT , st_2 , t_1 , brush b , C_{sm} to battery. 85

As soon as C_{sm} arrives opposite the terminals corresponding to the district exchange in which the fault originated relays C, T operate; ground, winding of T, brush G, ac_1 , winding of C, battery. Relay T is arranged to be of a quicker operation than C. The two relays lock up, T over t_3 , wiper a and, st_1 , and C via c_1 , e_3 , jr_1 . 90 95

Relay S_s , which responds to the impulses created in the fundamental circuit by the stepping of C_{sm} at its interrupter contacts, closes successively its back and front contacts. 95

The slow releasing relay L_b operates in response to the operation of relay S_s and this relay in turn operates relay C_t . Relay C_t 100 closes the circuit of the selector M_{sm} , battery, M_{sm} , winding of I, ct_1 , ct_2 , ss_1 , ground.

Relay L_b holds C_t during the pulsing and the selector M_{sm} completes its stepping when ss_1 opens at the end of the series. 105

Relay I is held operated during pulsing and releases at the end of the series of impulses, that is to say, when relay T, Fig. 2, operates.

The release of relay I indicates that C_{sm} in Fig. 2 has found the exchange which has created the alarm and since M_{sm} operates in synchronism with C_{sm} it is found in the same position. 110

Relay I on releasing closes a circuit for relay R and the In relay corresponding to the district of the alarm, ground, i_1 , ct_2 , R, oh_1 , brush b , Oc_1 , In , battery, relay R locks over r_1 , ct_4 . 115

The particular In relay to be operated will depend upon the position to which the M_{sm} switch is set which in turn will depend on the particular exchange having a fault. 120

The selector M_{sm} now moves into position 8; battery, M_{sm} , winding of I, ct_1 , r_2 , brush a INT , ground, relay T, Fig. 2, causes C_{sm} to move to position 8, also under its own interrupter, and at the same time it connects relay F in the fundamental circuit, over t_5 , f_0 , t_4 , ac_2 , b_3 . 125 130

In position 8, C_{sm} is operated over $f1$ and brush b . When M_{sm} reaches position 8 it operates O_f over brush a . The fundamental circuit is opened at o_f1 , thereby causing the release of F , Fig. 2, which opens the circuit of C_{sm} , now steps to position 9 and in leaving 8 opens the circuit of slow releasing relay S_{r1} which was operated in position 8. The circuit of relay T is also broken when C_{sm} 10 leaves position 8 and at $t4$ transfers the lead b of the fundamental circuit from relay F to the interrupter of C_{sm} , as before.

As has been stated above, the relay O_f opens the fundamental circuit in order to signal that M_{sm} is ready to receive an alarm 15 signal for urgent or non-urgent faults.

The momentary opening of the fundamental circuit by relays O_f and C_2 causes the relay S_s to fall back and operate M_{sm} . 20 After the closure of the fundamental circuit, relay S_s is again operated and M_{sm} completes its ninth step. Both selectors are now in position 9.

Relay O , Fig. 2, now operates; battery, 25 winding of O , $c2$ brush a , $s1$, ground.

In position 8, relay S_{r1} , Fig. 2, operated via brush c in series with the lower winding of T .

Assuming that the fault which has created 30 the alarm is of the non-urgent variety, no new impulse will be produced in the fundamental circuit leading from Fig. 1 to the "center" exchange and in consequence relay S_{r1} , in releasing slowly, closes $s_{r1}2$ thereby 35 energizing F_o . Contacts f_o2 open the b lead to the "main" exchange and f_o3 releases S_t while f_o1 operates relay E via $c3$. The opening of the "b" wire causes the release of relay S_s in Fig. 3 which in its turn releases relay 40 S_b , so that M_{sm} returns home via $c6$, brush c , and INT .

With relay C_t released the circuit of relay P_c will be open at the moment when M_{sm} passes to position 10. The relay In which 45 was operated in series with relay R has locked up via $in1$, RK , P to earth, contacts $in3$ are connected to the lamps $L1$, $L2$, $L3$, etc. Thus the particular In relay operated will operate one of the lamps which will indicate the 50 exchange in which the fault is present, a separate lamp being provided for each exchange.

If the fault which has occurred is of the urgent variety a series of impulses are produced in the fundamental circuit between 55 Fig. 1 and the "center" exchange Fig. 2 which continues after the switch C_{sm} has reached position 9 in response to the first impulse.

Relay S responds to the first of these 60 impulses after C_{sm} is in position 9 and steps C_{sm} via brush b , $o1$, and $s1$. S in deenergizing also closes a circuit for the slow relay S_{r1} via S_2 and $o2$.

C_{sm} therefore advances to position 10 when 65 E operates via $c3$, brush a , and $s1$.

In passing from position 9 to 10, C_{sm} opens the fundamental circuit at its interrupter contacts thereby causing a momentary deenergization of relay S_s , Fig. 3, which drives M_{sm} into position 10. In this position, the circuit of F_o in Fig. 2 will be completed to drive M_{sm} home but in the meantime relay P_c will have operated; battery P_c $h3$ brush b , R , $c2$, it to ground. By the time L_b falls back to release C_t , in response to the operation of F_o , relay P_c will have locked up over its contact 3 to ground on RK , in parallel with the particular In relay which has operated. 70

Owing to the fact that relay P_c is energized, the lamp which was connected up by the In relay is now connected to the interrupter INT 2 and the selected lamp instead of glowing continuously is caused to flash, thereby indicating that the fault is urgent. 80 Relay C_t will have released when F_o operated, after the switches moved into position 10, and over $c5$ and $in2$ a circuit is closed for relays O_e and H_o in parallel, and these relays lock up over $h1$ and the key RK to ground, 85 and transfer the lead coming from the arc b of M_{sm} , from relay In to the corresponding relay Inl . When a new alarm occurs everything takes place as described above except that the relay Inl is actuated in place of relay In . 90

The operation of any one of the In_1 relays will complete a circuit for relay O_h , from $c5$, via in_5 .

If therefore an alarm should occur in a 100 third district exchange, when the selector M_{sm} arrives opposite the terminals corresponding to the district which creates this alarm relay R will find its circuit open at contact o_h1 . In this position relay O_a is energized from battery, winding of O_a , o_h2 , r_3 , brush a of MSM to ground. Relay O_a operates a special alarm OAL indicating that a 105 third alarm is present, but cannot be recorded through lack of recording apparatus. 110

Due to the fact that relay R is not operated the restoring circuit of selector M_{sm} remains open and in consequence there will be no momentary opening of the fundamental circuit indicating to the center in Fig. 2 that it can send the signal giving the source of an alarm. In order to record this third fault it is merely necessary to open the key RK momentarily thereby releasing the two fault indications already recorded. 115

The third fault can now be received in the same manner as previously described.

In the embodiment shown in the drawings the faults at the different district exchanges, 120 which will be connected as Fig. 1 to the center at Fig. 2, are communicated to the "main" exchange Fig. 3 over a common junction.

It is obvious however that if desired a plurality of junctions might be provided between the "center" and the "main" exchange and 130

5 a separate junction might be allotted to each district for the transmission of alarm signals to the main. In this case the particular junction over which the alarm signal is transmitted will give an indication at the main as to the particular district exchange in which the fault has occurred.

10 In the case of faults at the "center" exchange, relays in a fault circuit individual to center and corresponding to that shown for an incoming junction, are directly operated for urgent and non-urgent alarms, and the fault indication is repeated in a similar manner to that already described.

15 5 It is obvious that means could be provided at the "center" exchange if desired to respond to the impulse or impulses from the district exchange and to indicate the exchange at which the fault has occurred and/or the type 20 of fault, without repeating the indication to the "main" exchange.

What is claimed is:

25 1. In a signaling system, fault indicating means, a line, and means for transmitting a different number of impulses over said line responsive to the particular type of fault indication present.

30 2. In a signaling system, a first and a second exchange, a line connecting said exchanges, fault indicating means at said first exchange, means for transmitting different types of signals from said first exchange in accordance with the type of fault present and means at the second exchange for discriminating between different types of signals to indicate the type of fault present at the first exchange.

35 3. In a signaling system, two exchanges, fault indicating means at one exchange, a line between said exchanges, means for transmitting a different number of impulses over the line from said one exchange in accordance with the particular type of fault present, and means at the other exchange responsive to said impulses for indicating said different types of faults.

40 4. In a signaling system, a first, a second and a third exchange, a line connecting said first and second exchanges, a line connecting said second and third exchanges, fault indicating means at said first exchange, means for signaling from said first exchange in accordance with the type of fault present, means at said second exchange for discriminating between different types of signals, means at said second exchange responsive to different types of signals for transmitting corresponding signals over the line to the third exchange, and means at the third exchange for discriminating between different types of signals received to indicate the type of fault present at said first exchange.

45 5. In a signaling system, a first, a second and a third exchange, a line connecting said first and second exchanges, a line connecting

70 said second and third exchanges, means for signaling from said first exchange over the line to the second exchange in accordance with the type of fault present at said first exchange, means at said second exchange responsive to the signals incoming from said first exchange for transmitting corresponding signals over the line to the third exchange, and means at said third exchange for detecting said different types of signals and means for visually indicating said different types of signals received at said third exchange.

75 6. In a signaling system, a plurality of unattended exchanges, an attended exchange, lines between said unattended exchanges and the attended exchange, fault indicating means at said unattended exchanges, means for transmitting different types of signals from said unattended exchanges over the cor. 80 responding lines to said attended exchange in accordance with the type of fault present, and means at the attended exchange for indicating the particular unattended exchange 85 in which the fault has occurred, and means for indicating the type of fault present.

90 7. In a signaling system, a plurality of first exchanges, a second exchange and a third exchange, lines between said first exchanges and the second exchange, a line between the second exchange and the third exchange, fault indicating means at said first exchanges, means for signaling from any of said first exchanges over the corresponding lines to the second exchange in accordance with the type 95 of fault present at said first exchanges, and means responsive to the signals incoming to the second exchange for transmitting corresponding signals to the third exchange and means at said third exchange responsive to the signals incoming to said exchange for identifying any of the first mentioned exchanges signaling to the second exchange and for discriminating between the different types of signals to indicate the type of the fault present at any of said first exchanges.

100 8. In a signaling system, a plurality of first exchanges, a second exchange and a third exchange, lines connecting said first exchanges to said second exchange, a line connecting said second exchange to said third exchange, fault indicating means at said first exchanges and means for signaling from said first exchanges in accordance with the type 105 of faults present, a step-by-step switch in the second exchange, a step-by-step switch in the third exchange, means for operating said switches in synchronism in response to signals incoming from any of said first exchanges, means at said third exchange operative in response to the setting of the switches for identifying any of said first exchanges having transmitted signals to the second exchange, and means for discriminating between different types of signals at said third 110 115 120 125 130 exchange.

exchange to indicate the type of the fault
present at the first exchanges having trans-
mitted signals to said second exchange.

In witness whereof, we hereunto subscribe
5 our names this 8th day of October 1931.

WILLIAM HATTON.
ERNEST J. ROUSSEAU.
